UNITED STATES PATENT OFFICE.

EMMETT C. HALL, OF DELRAY, FLORIDA.

TYPEWRITER KEYBOARD.

Application filed September 8, 1922. Serial No. 586,912.

To all whom it may concern:

Be it known that I, EMMETT C. HALL, a citizen of the United States, residing at Delray, in the county of Palm Beach and State of Florida, have invented certain new and useful Improvements in Typewriter Keyboards; and I do hereby declare the following to be a full, clear, and exact description of the invention, such as will enable others skilled in the art to which it appertains to make and use the same.

The object of the invention is to provide a keyboard for typewriting machines whereby the facility of operation is increased and particularly whereby the positioning of the hands on the keyboard is directed with accuracy and convenience to the operator with special reference to touch writing and the encouragement of operators to employ the touch system; and furthermore with a view to facilitating the acquirement and practice of the art of typewriting by the blind; and furthermore to provide a construction whereby the rapidity of operation is increased by minimizing the necessary movements of the hands and the strokes of the several fingers in the individual manipulation of the keys; and with these general objects in view, the invention consists in a construction, combination and relation of parts, of which a preferred embodiment is illustrated in the accompanying drawings, wherein:

Figure 1 is a front view of a keyboard embodying the invention, showing the same in connection with a typewriting machine of the conventional type which is indicated however merely in outline.

Figure 2 is a plan view of the keyboard,

Figure 3 is a similar view of the keyboard, wherein the key heads are square instead of being of the diamond form shown in Figure 2,

Figure 4 is a longitudinal sectional view of the keyboard on the plane indicated by the line 4—4 of Figure 2,

Figures 5, 6 and 7 are respectively detail sectional views on the plane indicated by the lines 5—5, 6—6 and 7—7 of Figure 2.

The keyboard indicated generally at 10 represents a conventional or standard arrangement of character key heads, shift keys and the like which are arranged however to provide a practically unbroken surface, in that the key heads are of angular form in plan and are provided with match-

ing or mating edges arranged in close relation, with just sufficient space to permit independent movement of the heads without frictional resistance, to the end that the fingers of the operator's hands may slide freely in any and all directions over the surface thereof without meeting any obstruction or edge tending to impede such movement. The keyboard in other words is of such a construction as to suggest its manufacture from a single slab or plate of suitable material sawed or cut on lines to separate the portions forming the individual key heads separated only by spaces representing saw kerfs or the like and presenting what may properly be termed an unbroken surface composed of the separately operable key head elements. The lines of division or separation between the key heads are arranged longitudinally as indicated at 11 and transversely as indicated at 12 and in the construction illustrated in Figures 1 and 2 these transverse lines are diagonally disposed, whereas in the form shown in Figure 3, the transverse lines are broken or interrupted with the several portions thereof perpendicular to or at right angles to the longitudinal lines, as indicated at 12^a. The form shown in Figure 2 with the diagonal transverse lines is preferred for the reason that should there be any looseness of the key heads incident to wear or otherwise, the fingers of the operator's hand in sliding from one position to another are not subject to contact with angles of the key heads and therefore to any distracting conditions.

The keyboard from end to end is of undulatory form with main guiding or indicating grooves 13 and 14 diagonally and transversely traversing the same and designed as guides for the middle or long fingers respectively of the left and right hands of the operator and supplemental guiding grooves or depressions 15 and 16 raised slightly from the planes of the grooves 13 and 14 for the third or ring fingers of the respective hands of the operator. Between these guiding grooves the keyboard is arched as indicated at 17 and toward its extremities the keyboard surface is elevated as indicated at 18 and 19. This undulating conformation of the surface of the keyboard is designed to bring the several series of key heads at opposite sides of the guiding or indicating grooves or features 13 and 14 within convenient reach of the other or shorter

5 fingers of the hands of the operator, to the end that in operation the several fingers may have practically the same distance to travel in order to cause the necessary operation of the keys allotted thereto or falling within their zone of operation. In other words, 10 with the middle fingers of the hands of the operator in the main guiding grooves, the other fingers of the hands rest comfortably and lightly and naturally upon the adjacent keys on either side thereof in such a position that practically the same movement of any finger will effect the desired operation of the key over which the finger is located. This 15 undulatory conformation is maintained transversely on diagonal lines which are substantially parallel for the two hands, throughout the width of the keyboard, so that as the hands are moved forward and 20 rearward or from and towards the operator in accordance with the direction prescribed by the main guiding grooves, the other fingers of the hands are correspondingly positioned over the different keys which are arranged parallel with or in series parallel with the said grooves.

Moreover, as a means of facilitating the 30 positioning of the hands in their movement from and towards the operator and the centering of the fingers over the keys to be operated by the fingers in different positions of the hands, the keys are preferably provided with centering depressions 20 of a depth merely sufficient to be felt by the tips of the 35 fingers as a guide in operation.

Thus the operator in placing the hands upon a keyboard constructed as described, finds the proper location for the hands with 40 relation to the keyboard without inspecting the latter and merely by the fact that with the hands in a natural position, the middle fingers will find the guiding grooves and immediately the other fingers find their proper positions on the related keys. With 45 the hands properly positioned, the several keys of the board can be selected merely by movements of the hands from and towards the operator and without inspection. For this reason the keyboard is specially adapted 50 for the use of the blind, not only in learning the use of the machine but in the later expert manipulation thereof, and as a means

of teaching and encouraging the use of the touch system in operation, the construction indicated is an efficient and reliable guide which can be redited to practice as soon as the operator has learned the order in which the characters are arranged on the keyboard and which as above indicated is in accordance with the standard adopted by the manufacturers of commercial typewriting machines.

What is claimed is:

1. A typewriter keyboard having keys provided with matching edges arranged in juxtaposition and with the facing edges of the different keys at the upper surface in flush relation to produce a continuous substantially imperforate bearing surface for the fingers of the operator's hands, said surface being provided with one or more finger guiding grooves common to a plurality of keys.

2. A typewriter keyboard having keys provided with matching edges arranged in juxtaposition to produce a continuous bearing surface for the fingers of the operator's hands, said surface being provided with transverse diagonally disposed substantially parallel guiding grooves for the middle fingers of the hands, said surface being arched intermediate said grooves, said surface having a groove on the sides of the first mentioned grooves opposite to the arch, and said surface having elevated portions on the sides of the second grooves opposite to the first grooves.

3. A typewriter keyboard having keys provided with matching edges arranged in juxtaposition to produce a continuous bearing surface for the fingers of the operator's hands, said surface being provided with transverse guiding grooves for the middle fingers of the operator's hands, and the adjacent portions of the surface being undulated to bring the related keys within uniform reach of the other fingers of the hands.

In testimony whereof I affix my signature in presence of two witnesses.

EMMETT C. HALL.
